UNITED STATES PATENT OFFICE

BERT J. ANDERSON AND RICHARD T. TURNER, OF HAMMOND, INDIANA

DESIGN FOR A VELOCIPED

Application filed March 27, 1933. Serial No. 47,613. Term of patent 14 years.

To all whom it may concern:

Be it known that we, BERT J. ANDERSON and RICHARD T. TURNER, citizens of the United States, residing at Hammond, in the county of Lake and State of Indiana, have invented a new, original, and ornamental Design for a Velocipede, of which the following is a specification, reference being had to the accompanying drawing, forming part thereof.

Figure 1 is a perspective view of a velocipede, showing my new design.

Figure 2 is a sectional view of the head portion of the velocipede taken on the line 2 of Figure 1.

We claim:

The ornamental design for a velocipede, as shown.

BERT J. ANDERSON.
RICHARD T. TURNER.
